UNITED STATES PATENT OFFICE

FRANZ K. SIXTHOR, OF WHITINSVILLE, MASSACHUSETTS, ASSIGNOR TO WHITTIN MACHINE WORKS, OF WHITINSVILLE, MASSACHUSETTS, A CORPORATION OF MASSACHUSETTS

APPARATUS FOR WET TREATMENT OF HANKS

Application filed December 10, 1930. Serial No 501,321.

This invention relates to apparatus used for carrying out different operations in the wet treatment of hanks of thread, yarn, silk or other materials. In such apparatus, the 5 hanks of material are mounted on rods extending crosswise below a tank containing a suitable liquid for bleaching, dyeing or other treatment of the material which is allowed to drip or spray on the hanks. A second tank 10 below the hanks and cross rods serves to collect surplus liquid. Means is provided for advancing the rods between the tanks step by step from one end of the tanks to the other. It is also desirable to rotate the rods in their 15 successive positions, so that all parts of each hank will receive uniform spraying and treatment.

It is the general object of my invention to provide improved actuating mechanism for 20 thus intermittently advancing and rotating the rods.

My improved mechanism is simple in construction and reliable in operation and is particularly designed to prevent entrance of liquid 25 to the actuating mechanism.

My invention further relates to arrangements and combinations of parts which will be hereinafter described and more particularly pointed out in the appended claims.

30 A preferred form of the invention is shown in the drawings, in which

Fig. 1 is a sectional end elevation of my improved apparatus; and

35 Fig. 2 is a partial side elevation thereof on an enlarged scale and looking in the direction of the arrow 2 in Fig. 1.

Referring to the drawings, I have shown the hanks H mounted on rods 10 extending crosswise below a tank X adapted to contain 40 any desired liquid for the treatment of the hanks. A second tank Y is positioned below the hanks to receive drippings or surplus liquid. The ends of the rods 10 are normally supported on the peripheral surfaces of adjacent rolls 14.

Each roll 14 is mounted on a sleeve 16 (Fig. 1) rotatable in a fixed bearing 17 formed in one side wall of a casing 18. A worm gear 20 is mounted at the inner end of 45 the sleeve 16 and is engaged by a worm 21 on

a driving shaft 22 extending lengthwise of the casing 18 and supported in suitable bearings 24 within said casing.

So long as the rods 10 are supported on and between the rolls 14, they are continuously rotated and present fresh portions of the hanks to be sprayed by the liquid contained in the tank X.

In order to give the rods an intermittent advance movement in a direction lengthwise of the tank X, I provide lifter blocks 30, loosely mounted on crankpins or studs 31 secured in the ends of crank arms 32. The arms 32 are mounted on cross shafts 33 rotatable within the sleeves 16 previously described.

The rear ends of the shafts 33 are also supported in bearings 40 on the outer side wall of the casing 18. A worm gear 41 is mounted on each cross shaft 33 and is engaged by a worm 42 on a driving shaft 43 extending lengthwise of the casing 18 and also supported for rotation in the bearing blocks 24 previously described.

The lifter blocks 30 are concavely recessed at their upper ends to fit under the rods 10 and to securely support the rods as they are advanced to their next forward position. Each lifter block 30 has a downwardly extending portion provided with a stud 46 which extends into a recess 47 formed in a depending portion of a link 48. One of these links 48 is provided for each adjacent pair of lifter blocks 30 and acts to maintain the blocks in parallel vertical relation as they are given an orbital movement by the crankpins or studs 31.

As the lifter blocks move upward, they engage under the associated rods 10 and advance the rods through the successive positions indicated at the right in Fig. 2 to a position of engagement with the next forward pair of rotating rolls 14.

A collar 50 (Fig. 1) is mounted on each cross shaft 33 and holds the associated crank arms 32 snugly against the outer end of the sleeve 16. A tightly fitting cover 52 extends lengthwise of the casing 18. With this construction the possibility of leakage of liquid from the rods 10 to the actuating mecha-

nism in the casing 18 is reduced to a minimum, as the driving mechanism is entirely enclosed in a tight fitting casing and there is no chance for liquid to enter except through 5 the bearings which support the sleeve 16 and cross shaft 33. These bearings may be made very close fitting and may be easily and suitably packed to prevent access of liquid thereto.

10 Furthermore, the only entrance of moving parts to the casing 18 is at the side, and the top of the casing may be made continuous and very tight fitting. This provision of effective means to prevent entrance of liquid 15 to the driving mechanism is very important in this class of apparatus, as the liquid in the tank X is often of an acid or corrosive nature.

Having thus described my invention and 20 the advantages thereof, I do not wish to be limited to the details herein disclosed, otherwise than as set forth in the claims, but what I claim is:—

1. In an apparatus for wet treatment of 25 hanks, having a spraying device and a plurality of cross rods for suspending hanks below said device, in combination, a series of rolls for supporting said cross rods, means to support said rolls in adjacent but spaced 30 relation, means to rotate said rolls, and additional means rotatable concentric with said supporting means and effective to intermittently lift and advance said cross rods to positions for engagement by successive pairs of 35 rolls.

2. The combination in an apparatus for 40 wet treatment of hanks as set forth in claim 1, in which said additional means comprises rotated crank arms and crank-pins, links connecting said crank-pins in pairs, and rod-engaging devices movable with said crank-pins and held in parallel vertical position by said links.

3. The combination in an apparatus for 45 wet treatment of hanks as set forth in claim 1, in which said additional means comprises rotated crank arms and crank-pins, links connecting said crank-pins in pairs, and lifter blocks mounted on said crank-pins and engaging the ends of said cross rods, each block having an operative connection with one of 50 said links, whereby the blocks are held in parallel vertical position.

4. The combination in an apparatus for 55 wet treatment of hanks as set forth in claim 1, in which said additional means comprises rotated crank arms and crank-pins, links connecting said crank-pins in pairs, and lifter blocks mounted on said crank-pins and engaging the ends of said cross rods, each block having a pin and slot connection with one of 60 said links, whereby the blocks are held in parallel vertical position.

5. The combination in an apparatus for 65 wet treatment of hanks as set forth in claim

1, in which said rolls are mounted on rotated sleeves, and in which said additional means comprises shafts rotatable in said sleeves.

6. The combination in an apparatus for 70 wet treatment of hanks as set forth in claim 1, in which said rolls are mounted on rotated sleeves, and in which said additional means comprises shafts rotatable in said sleeves, said sleeves and shafts being separately and independently driven.

7. In an apparatus for wet treatment of 75 hanks, having a spraying device and a plurality of cross rods for suspending hanks below said device, in combination, a casing extending lengthwise of said device and tightly 80 closed at the top, a plurality of sleeves rotatably mounted in fixed bearings in one side of said casing, cross shafts rotatably mounted in said sleeves, said sleeves and cross shafts constituting two sets of rotating members, 85 rod-rotating rolls supported on one set of said rotating members and rotatable about the fixed axes thereof, rod-lifter devices actuated by the other set of said rotating members and effective to successively advance said 90 rolls from one pair of supporting rotating members to another, and separate driving means in said casing for said sleeves and for said cross shafts.

In testimony whereof I have hereunto 95 affixed my signature.
